UNITED STATES PATENT OFFICE.

JOHN DAVID, OF GENEVA, SWITZERLAND, ASSIGNOR TO J. DAVID & CIE., OF GENEVA, SWITZERLAND.

MOTOR-CYCLE.

No. 926,390.

Specification of Letters Patent.

Patented June 29, 1909.

Application filed October 3, 1906. Serial No. 337,174.

To all whom it may concern:

Be it known that I, JOHN DAVID, mechanician, citizen of Republic of Switzerland, residing at Geneva, in the Canton of Geneva 5 and Republic of Switzerland, have invented certain new and useful Improvements in Motor-Cycles, of which the following is a specification.

My invention relates to improvements in bicycles and particularly to that class of bicycles known as motor-cycles; and an object of my invention is to provide a bicycle of the class described which will be simple in construction, comparatively cheap in manufacture and of high power and efficiency combined with small weight. In such a motor-cycle the internal combustion engine must be of strong and compact construction and must have its dimensions reduced as much as possible. To obtain a certain high power from an engine of small dimensions, the pistons must have a high speed; and this requirement has led to difficulties in regard to the safe working of the motor. The engine used in my new motor-cycle is of the two-cylinder type and is very compact in construction and capable of working regularly, safely and efficiently at a high speed.

My invention consists of the motor-cycle 30 hereinafter described and claimed.

In the drawings illustrating the principle of my invention and the best mode now known to me of applying that principle, Figure 1 is a side elevation, partly in section, one 35 of the sides of the casing being shown removed for clearness; Fig. 2 is a detail of the mounting for the valve-operating mechanism; Figs. 3 and 4 are details of the mounting of the piston and connecting-rod; Figs. 40 5 and 6 are details of the muffler; and Fig. 7 is an elevation of my new motor cycle.

The casing *a* carries the two cylinders *b* which are connected to the casing in any suitable manner, as by being screwed there- 45 to. Between the cylinders *b* is mounted a carbureter *z* and cast integral with the casing *a* is a support *t* which carries an electromagnetic firing device shown conventionally at *t*¹. The cylinders *b* are provided with valve 50 boxes *c*^x and these are connected by a tube *z*^x through which the fuel is led from the carbureter *z* to the valve boxes *c*^x.

Working in the cylinders *b* are the pistons *c* one of which is connected to the crankshaft 55 pin *f* by a connecting rod *d*¹, while the other

is connected to the crankshaft pin by the rod *d*²; but these rods *d*¹, *d*² are not linked directly on the crankshaft pin *f*. On the contrary the rod *d*¹ has on its lower end a fork-shaped part *d*³ in which is fitted a sleeve *e* 60 on which oscillates with slight friction the other rod *d*² (Figs. 1 and 3). The crankshaft pin passes through the sleeve *e* and receives the thrust of the rods *d*¹, *d*²; but the thrust is transmitted to the crankshaft pin *f* 65 through the sleeve *e* and is thereby distributed over the whole length of the pin *f*, whereby the pressure per unit of length of the pin *f* is reduced and the power is transmitted under better conditions than would 70 otherwise be the case.

The rods *d*¹, *d*² are connected to the pistons *c* by means of the cross-pins *n* carried by the pistons and upon which the rods are free to oscillate. The cross-pins *n* are split at their 75 ends and are there pierced with conical holes *n*¹, *n*². The latter are threaded to receive the conical screws *o*¹, *o*², by the insertion of which in said holes the walls of the latter are spread apart, whereby the cross-pin *n* is firmly 80 wedged in place in the piston without deformation of the latter. (See Figs. 3 and 4). By this construction an accurate adjustment of the piston in the cylinder is made possible, 85 an important feature in high speed work.

The gears *g*, *h* and *i* are provided for operating the valves and the ignition device through any suitable mechanism, many forms of which are so well known as to require no illustration and no further description here. The pinion *g* is mounted upon the engine-shaft *g*¹ and the pinion *i* upon a shaft *i*¹ fitted in perforations in the rim of the casing. The intermediate pinion or gear *h* 90 is mounted upon a stub-shaft *k* carried by a steel plate *l* which is fastened to the casing *a* by means of the screws *m*. The strong and stiff steel plate *l* serves to prevent the deformations which would result from fastening 95 the stub-shaft *k* to the casing *a* directly.

The exhaust gases pass to a muffler shown in detail in Figs. 5 and 6 and consisting of a cylinder *p* closed at its ends by the plates *q*¹, *q*² in which are mounted, respectively, the pipes *r*¹, *r*², each of which is open at its outer end and is formed with holes in its side wall. The pipe *r*¹ is threaded at its outer end for connection with the exhaust pipe and the exhaust gases flow through the holes in the 105 side wall of the pipe *r*¹ out into the cylinder 110.

or chamber p and, the inner end of both the pipes r^1, r^2 , being closed, the gases then flow into the pipe r^2 through the holes in its side wall and escape through the outer open end 5 of the pipe r^2 . A screw-rod s holds the plates or heads q^1, q^2 tightly against the cylindrical wall p during the operation of the engine; but by merely loosening the screw-rod, the plates q^1, q^2 may be removed and the interior 10 of the muffler exposed to view for cleaning and repair.

The casing a is provided with suitable clamp members q^x by which the engine is clamped to the tubes 10, which form a part 15 of the bicycle frame (Fig. 7.)

The bicycle to which the engine is clamped is driven by the latter by means of a round belt 11 which passes over grooved pulleys 12, 13. This driving belt's tension may be 20 varied by the belt-tightener shown in Fig. 1. Here the tension pulley u is mounted in one end of an arm v the other end of which is pivotally connected to the casing a . To one of 25 the cylinders b is pivotally fastened or hinged a lock-plate y formed with an oblique hole through which passes the upper part of a tension-control rod x the lower end of which is pivotally secured to the swinging arm v which carries the jockey pulley u . The upper 30 end of the tension-control rod x is formed with a hook and is readily accessible to the

rider. When he pulls up on the rod x , the lock-plate y is swung upwardly, until it allows the rod x to pass freely through the hole in the lock-plate. The tension of the belt 35 having been adjusted, the tension-control rod x is forced downwardly, carrying the lock-plate y with it; and as the lock-plate approaches the horizontal, the oblique walls of the hole in it serve to lock the rod x in place. 40

I claim:

A motor-cycle consisting of the combination with frame members; and wheels mounted therein for supporting the same; of an engine-casing fastened to said frame-members; a plurality of cylinders mounted upon said casing; pistons which work in said cylinders; an engine-shaft driven by said pistons; a carbureter mounted between said cylinders; a firing device carried directly by 50 said casing; a belt which connects said engine shaft with one of said wheels; a belt-tightener carried by said casing for regulating the tension of said belt; and means carried by one of said cylinders for moving said belt tightener. 55

In testimony whereof I have affixed my signature in presence of two witnesses.

JOHN DAVID.
